2,553,045

PUMP AND MOTOR HYDRAULIC SYSTEM

Lawrence F. Jaseph, Memphis, Tenn., assignor to
 Rotary Lift Company, Memphis, Tenn., a corporation of Delaware

Application October 24, 1942, Serial No. 463,191

29 Claims. (Cl. 60—52)

1

The present invention relates to improvements in hydraulic control and more particularly to improvements in control valves for hydraulically actuated devices such, for instance, as elevators. The present invention is an improvement over the invention disclosed in my co-pending application, Serial No. 377,959, filed February 8, 1941 (now Patent No. 2,355,164, granted August 8, 1944).

The present invention relates primarily to a control valve for hydraulic elevators that are raised by pressure obtained directly from a motor driven pump and lowered by gravity. The valve enables elevators of this type automatically to be controlled in such a manner as to obtain gradual smooth acceleration and deceleration when the elevator is either raised or lowered; to provide a plurality of speeds in both directions, one of which is a slow speed enabling landings to be made accurately and enabling the elevator to be moved small distances; to provide gradual stopping of the elevator in the event of a power failure; to limit the hydraulic pressure to a safe maximum value; and to permit the pump driving motor to be started and accelerated to full speed with but a very small load.

One of the objects of the invention is to provide a new and improved control valve for a hydraulically actuated device supplied with fluid from a motor driven pump so constructed and arranged as to enable the motor to be started and accelerated to full speed with but a very small load.

Another object of the invention is to provide a new and improved control valve capable of limiting the pressure obtaining in the system and applied to the actuated device to a safe maximum value.

A further object of the invention is to provide a new and improved control valve wherein a valve member of unitary construction provides both the motor starting and pressure limiting features to which reference has been made.

A further object of the present invention is the provision of a new and improved valve of the character described capable of effecting smooth and gradual acceleration and deceleration of the actuated device and, further, wherein the valve member of unitary construction is utilized to provide not only the motor starting and pressure limiting constructions, but also acceleration and deceleration when the actuated device is moved by pressure obtained from the motor driven pump.

Another object of the present invention is the

2

provision of a new and improved control valve of the character described capable of controlling the flow of fluid from the pump to the actuated device to effect movement of the device in one direction and from the actuated device to a fluid reservoir to effect movement of the device in the opposite direction.

A further object of the present invention is the provision of a new and improved valve of the type last mentioned with means for indicating both the volume and direction of the flow of fluid.

A still further object of the present invention is the provision of a new and improved valve of this type wherein the indicating means is utilized in controlling the valve so as to produce a constant flow of fluid to the actuated device.

A further object of the present invention is to provide a control valve of the character described with movement restraining means so controlling the valve that flow of fluid to and from the actuated device can be effected at a uniformly changing rate.

Another object of the present invention is the provision of a valve of the character described that is controlled by a pilot valve and wherein the pilot valve is so controlled that during a period of operation the flow through the valve is at a uniformly changing rate and wherein in case the rate departs from this uniformly changing rate, the pilot valve is controlled to bring back the rate to this uniform value.

A further object of the present invention is to provide a new and improved control valve including a combined pilot operated bypass valve and an overpressure relief valve of the spring biased type wherein the same structural parts are used to perform both functions without interference, and wherein it is not necessary to relax the relief valve spring when the bypass is opened.

A further object of the present invention is the provision of a new and improved overpressure relief valve.

Other objects and advantages of the present invention will become apparent from the ensuing description, in the course of which reference is had to the accompanying drawings in which:

Fig. 1 is a diagrammatic illustration showing how the present invention may be applied to one type of elevator system;

Fig. 2 is a diagrammatic illustration of electrical circuits embodied in the system shown in Fig. 1 to illustrate how the present invention may be applied to one type of system;

Fig. 3 is a top plan view of the control valve of the present invention which forms an important part of the system illustrated in Figs. 1 and 2;

Fig. 4 is a side elevational view of the control valve;

Fig. 5 is an enlarged cross-sectional view of the valve, the view being taken along the line 5-5 of Fig. 3 and also along line 5-5 of Fig. 6;

Fig. 6 is a view similar to Fig. 5, the view being taken along the line 6-6 of Fig. 5;

Fig. 7 is an enlarged fragmentary cross-sectional view, the view being taken along the line 7-7 of Fig. 3;

Fig. 8 is an axial cross-sectional view through a pilot valve forming part of the main control valve illustrated in the preceding figures;

Fig. 9 is a top plan view, with cover removed, of the structure within the control box located at the right of Fig. 3;

Fig. 10 is a side view of the structure within the control box, a portion of the structure being omitted better to illustrate other details of construction; and

Fig. 11 is a diagrammatic view showing in schematic form the operative relation of the several elements of this control system.

Before proceeding with a detailed description of the control valve forming the primary feature of the present invention, it may be well briefly to describe one type of elevator installation embodying the control valve. In so doing, reference will be had to Figs. 1 and 2 illustrating the mechanical and electrical features, respectively, of one type of system to which the valve may be applied. This system is of the type controlled by a manually controlled car switch, but it should be understood the system is but one of a number to which the valve of the invention may be applied. The valve may be readily adapted to automatic control systems of the momentary or constant pressure push-button controlled type, and also to systems having automatic leveling, as will become apparent from the following description.

Referring first to Fig. 1, it may be noted that the elevator car 10 is supported at the top of a plunger 12 mounted for vertical reciprocating movement in a cylinder 14. The elevator is raised by supplying fluid, preferably oil, under pressure to the cylinder and the elevator is lowered by gravity by allowing the oil to flow from the cylinder into a reservoir.

Oil is supplied to the cylinder under pressure by means of a pump 16 of the constant displacement type and driven by an electric motor 18. Oil is supplied to the suction side of the pump from a reservoir 20 through a conduit 22 and the discharge side of the pump is connected through a conduit 24 to the control valve 26 of the present invention. The control valve is connected by a conduit 28 to the elevator cylinder 14 and by a conduit 30 to the reservoir.

The movement of the elevator in the illustrated system is controlled by a car switch 32 mounted within the elevator and operable from a neutral or stop position into high and low speed positions for either raising or lowering the elevator at high or low speed. The elevator control includes also normally closed upper and lower limit switches 34 and 36 opened at limits of movement by a switch operating member 37 secured to the car. The various switches are connected electrically in the manner shown in Fig. 2, the electrical conductors being enclosed in suitable conduits 38 of which the portion 40, connected to

the car switch, is flexible. In the instant case, the elevator is shown as being movable between an upper landing 42 and a lower landing 44. It should be understood, however, that the number of landings will depend upon the particular installations of the elevator. Power is supplied to the motor and to the controls from a suitable source through a manual control switch 46 from which a conduit leads to a control box 48 including an electromagnetically operated motor switch.

Referring now to Fig. 2, it may be seen that the pump motor 18 is of the three-phase type and that its energization is controlled by a switch 50 operable by a solenoid 52, these being mounted in the control box 48. The motor, as already indicated, is utilized only when it is desired to raise the elevator, as the lowering of the latter is effected by gravity.

The control valve 26 of the present invention includes four solenoids that are selectively energized to effect raising and lowering of the elevator at high and low speeds. These solenoids are indicated by reference characters 54, 56, 58, and 60. When it is desired to raise the elevator at low speed, the solenoid 54 is energized, and when the elevator is to be raised at high speed, the solenoid 56 is energized. In similar manner, when it is desired to lower the elevator at low or high speed, the solenoids 58 and 60 are selectively energized. Inasmuch as the elevator is raised by pressure supplied from the pump, the pump is placed into operation when either of the solenoids 54 or 56 is energized and to accomplish this, the solenoids are each adapted to close a switch 62 in series with the solenoid 52 across two of the power lines. Consequently, when either of the solenoids is energized, the pump motor 18 is also energized.

The solenoids are selectively energized by the car switch which has been illustrated but diagrammatically. As the car switch handle 64 is moved in a counterclockwise direction to a first position, the solenoid 54 is energized to effect raising of the elevator at low speed. The solenoid is energized through a circuit including conductor 66, the upper limit switch 34, conductor 68, car switch 32, conductor 70, the solenoid 54, and conductor 72. If it is desired to raise the elevator at high speed, the car switch handle 64 is moved further in a counterclockwise direction, thereby deenergizing solenoid 54 and energizing solenoid 56, the latter being energized through a circuit corresponding to that for solenoid 54 except that the circuit extends through a conductor 74 instead of conductor 70.

To lower the elevator at low speed, the control handle 64 is moved in a clockwise direction. In a first position the solenoid 58 is energized to effect lowering of the elevator at slow speed. The solenoid is energized through a circuit including the conductor 66, a conductor 76 leading to the lower limit switch 36, conductor 78, the car switch, conductor 80 leading to the solenoid, and conductor 72. In a further clockwise position, the solenoid 60 is energized through a similar circuit except conductor 82 is substituted for the conductor 80. If desired, fuses 84 may be located in the control circuits for safety purposes.

Before proceeding with a description of the details of the control valve, it might be well briefly to set forth the main details of its construction and operation in a system such as that described. The valve assembly itself comprises primarily a check valve for preventing return

flow of oil from the elevator cylinder to the discharge side of the pump, a bypass valve for bypassing the oil from the discharge of the pump to the oil reservoir, a lowering valve, a mechanism for indicating the direction and volume of oil flowing through the valve (that is, oil flow to the cylinder from the pump or from the cylinder to the reservoir), a pilot valve controlling the bypass and lowering valves, the four valve control solenoids referred to, movement restraining devices, preferably dash pots, and suitable linkage mechanism for connecting the pilot valve to the solenoids and indicating mechanism.

To raise the elevator, the pump motor 13 is energized by energization of either one or the other of the solenoids 54 and 56. The bypass valve is normally open so that whenever the motor is started, it accelerates and brings the pump up to full speed very quickly and at a very light load since the oil is bypassed at a very low pressure. After a time delay determined by the setting of the dash pots, the pilot valve moves to a position such that the bypass valve is gradually closed by an increasing oil pressure so that oil is gradually supplied to the elevator cylinder. This action continues until the bypass is fully closed.

To stop the elevator when it is moving in an upward direction, the solenoid 54 or 56, whichever is energized at the time, is deenergized. The motor, however, continues to operate and the bypass is gradually opened. When the bypass opens to a sufficient extent, the elevator stops and the motor is deenergized by the opening of the switch, this being the switch 62.

If a slow raising speed is desired at any time, the solenoid 54 is energized. It operates to open the bypass to but a limited extent, whereby all but a definite quantity of the oil is bypassed to the reservoir.

To lower the elevator at high speed, the solenoid 60 is energized. It operates the pilot valve to a position such that the lowering valve is permitted to open to a desired extent corresponding to the desired speed. The lowering valve is automatically maintained at this opening. To reduce the lowering speed to a good leveling rate, the solenoid 60 is deenergized and the solenoid 58 energized. The main lowering valve then closes gradually to a position to produce the desired low speed where it remains until the solenoid 58 is deenergized. When this is done, the lowering valve gradually closes and brings the elevator to rest.

It may be noted, therefore, that the control valve may be readily controlled to effect raising or lowering of the elevator at either high or low speed. It thus lends itself not only to the illustrated manual type of control, but also to other types of manual control and to automatic control wherein the elevator is operated at high speed except in landing zones, at low speed in the landing zones and also automatically leveled, even if it should, for any reason whatever, go past some predetermined stopping point. The valve may be remotely controlled and easily controlled by the manual control and control members, such as switches positioned to be controlled in response to the car position.

Referring now more particularly to Figs. 3 to 6, inclusive, it may be noted that the control valve 26 comprises a casing or body 30 in the form of a casting provided with an inlet port 92 to which the pump discharge conduit 24 is connected, an outlet port 94 (see Fig. 3) to which the conduit 30 leading to the reservoir is connected, and what

may be termed a combined outlet and return port 96 through which oil flows to and from the elevator cylinder 14 through conduit 28. When the elevator is being raised, oil flows from the discharge side of the pump through the port 92 into a passageway 98, past a pivotally mounted gravity biased check valve 100, into a chamber 102, and then past an oscillatable vane 104, herein-after to be referred to as a speed vane and the purpose and functioning of which will be described in greater detail, into a chamber 106 and through the port 96 and conduit 28 to the cylinder. When the elevator is being lowered, oil flows from the cylinder into chamber 106 through the port 96, and then past the speed vane 104 into chamber 102, and past a then open lowering valve 108 into a return chamber 110 and thence to the reservoir through port 94 and conduit 30. During the lowering operation, the check valve 100 is closed to prevent return flow of oil to the discharge side of the pump.

The main operating parts of the valve mounted within the valve casing, other than the check valve 100 and speed vane 104, are the lowering valve 108 and a bypass valve 112. This bypass valve 112 is utilized when starting the pump motor, during the raising of the elevator, and also in providing overpressure relief.

Under normal conditions, i. e., when the elevator is stopped, the various operating parts occupy the positions in which they are indicated in Figs. 5 and 6. At this time, the check valve is closed, speed vane is in its central position to which it is resiliently biased, the lowering valve 108 is in closed position shutting off communication between chambers 102 and 110, and the bypass valve is open providing communication between the passage 98 and the return chamber 110.

Referring now more particularly to Figs. 5 and 6, it may be seen that the bypass valve 112 comprises a cylindrical valve 114 defining portion, the reduced inner end 116 of which fits closely in a port 118 providing communication between passageway 98 and chamber 110. It is provided with radial passages 120 which, in the indicated position of the valve, permit full flow of liquid from port 118 to the return chamber 110 without necessity of the valve being completely withdrawn from its seat. The opposite end of the valve is enlarged to form a piston 122 closely fitting in and reciprocable in a cylindrical piston chamber 124 formed in the body 30. The piston chamber is sealed by a closure cap 126 secured to flanges surrounding the piston chamber by any suitable means such as the bolts 128 shown in Fig. 6. Movement of the piston to the left, that is, toward the closure cap, is limited by the cap, against which a peripheral shoulder 130 on the piston is adapted to abut.

The bypass valve is biased toward its open position by a relatively light spring 132, which holds the piston against the closure cap or against a suitable stop ring (not shown, but which may be provided if it is desired to further limit the movement of the piston for purposes of adjustment when required).

The closure cap and left end of the piston define a pressure chamber 134, the pressure in which is controlled by a pilot valve, to be described hereinafter, in order to control the movement and position of the bypass valve. The pressure chamber communicates with the port 118 and passageway 98 through one or more (only one being shown) passages 136 extending

through the piston. The pressure chamber also communicates with the pilot valve through a conduit 136 communicating with the chamber through a nipple 140 suitably secured to the closure cap.

The overpressure relief is provided by a second valve defining piston 142 movable within a smaller piston chamber 144 formed in the piston 122. The piston 142 is normally biased outwardly by a relatively heavy spring 146 whereby the piston closes one or more passages 148 (only one being shown) in the larger piston. When excess pressures obtain in the system, the pressure in chamber 134 is sufficient to move the piston 142 inwardly against the spring to uncover these passages whereby the pressure existing in the chamber 134 is relieved by the flow of oil into the return chamber 110 and consequent opening of the bypass valve. In the event the excess pressure is not particularly great, the piston 142 uncovers but a small area of the passageway 148, this small area being provided by a tapered portion 150 formed near the outer end of passageway 148. Thus, small movement of the piston 142 will uncover but a small passage for escape of liquid but a greater movement will open a relatively large area for the escape of the liquid and rapid relief of pressure in the system.

The pressure at which overpressure relief is obtained may be adjusted by varying the compression of the spring 146. This compression is varied by means of an adjusting screw 152 which is held in adjusted position by a lock nut 154. The inner end of the adjusting screw bears against a cupped washer 156 bearing against the outer end of the spring. Inward movement of the piston is limited by a shoulder 158 in the piston 122 and outward movement by a snap ring 160 inserted in a groove in the piston 122.

The relief valve of the present invention is particularly advantageous in that the spring 146 is preloaded so that it will not be compressed materially as a result of pressures obtaining in the system until the pressures reach overpressure values. Even in this case the additional compression of the spring is slight. As a result, the spring is extremely unlikely to be broken as a result of fatigue. While the relief valve has been illustrated as embodied in a particular control valve, it should be understood that it is adapted to be used alone or in conjunction with other types of valves.

The lowering valve is best illustrated in Fig. 6, to which reference will now be had. It comprises a piston 164 fitting closely and reciprocable in a piston chamber 166. The piston carries a hard resilient disk 168 retained in place by a throttling cup 170 secured to the disk by a screw 172. The throttling cup assists in guiding the piston as it is fitted closely in a seat 174 formed in a partition 176 separating the return reservoir 110 from the chamber 102.

The lowering valve is normally closed, it being urged in closing direction by a relatively light spring 178 abutting against the outer face of the piston and against a closure cap 180 secured to flanges in the valve body by suitable means such as the bolts 182. A pressure chamber 184 is defined by the outer side of the piston and the closure cap. This chamber communicates with chamber 102 through one or more (only one being shown) passages 186 preferably formed in inserts 188 threaded into the piston.

The position of the lowering valve is also controlled by regulating the pressure in the

chamber 184. This pressure regulation is also effected by the pilot valve which is connected to the pressure chamber by a conduit 190 communicating with the pressure chamber through a nipple 192 secured to the closure cap.

The speed indicating vane 104 is movably mounted at the upper end of the valve body, as best illustrated in Figs. 5 and 7. The vane is rectangular in shape and is fitted closely but freely to move in a semi-cylindrical opening 194 in the valve body. The described construction provides two generally V-shaped ports 196 and 198 separated by a partition 200. The vane is preferably mounted in a closure cap 202 secured to the valve body as by a plurality of bolts 204 (see Fig. 3). The vane 104 is secured to a shaft 206 by a pin 208 and shaft 206 is mounted for oscillation in a pair of spaced apart bearings 210 mounted in the closure member. Leakage of liquid along the shaft is prevented by resilient packing 212 and endwise movement of the shaft is prevented by thrust collars 214 and 216, the latter of which is threaded into the closure member and provided with a recess to receive a collar 218 formed on the shaft.

The speed vane is biased to its central position (in which it is indicated in Figs. 5 and 7) by a spring 220, shown best in Fig. 9. When the speed vane is displaced in either direction from its centered position, the spring tends to return it with a positive force by reason of the spring being placed under considerable initial tension, as will be described shortly.

Inasmuch as the ports 196 and 198 are generally V-shaped, it may be seen that a small rotation of the vane uncovers only a small port area, but greater rotation uncovers a greater portion of the port.

The various controls, including the solenoids and bypass valve, are mounted in or secured to a control box 222. The control box comprises generally vertical and horizontal bed plate walls 224 and 226 and a removable cover 228. It is secured to the valve body by a plurality of screws 230 (see Fig. 4) passing through wall 224.

The previously referred to pilot valve, which is indicated generally by the reference character 232, is mounted underneath the wall portion 226 by a plurality of bolts 234. The pilot valve is controlled, as already indicated, by the selectively energizable solenoids 54, 56, 58, and 60, and also by the speed vane 104, all of which are connected to the pilot valve through a linkage mechanism now to be described.

Each of the solenoids includes a winding secured to a core 236 which, in turn, is secured by suitable brackets to upstanding supports formed integrally with the bed plate. The outermost supports 238 and 240 extend above the innermost supports and fixedly support a shaft 242 upon which is journaled a pair of levers indicated generally by reference characters 244 and 246.

The plungers 248 of the four solenoids are connected to the lever 244, whereby the latter is rotatable in opposite directions depending upon whether the raising solenoids 54 and 56, or the lowering solenoids 58 and 60 are energized and to different angular extents depending upon whether the high speed solenoids 56 and 60, or the low speed solenoids 54 and 58 are energized. The plungers are adjustably connected to the lever by identical structures so that it is thought necessary to describe but one of these and to

indicate the others by like reference characters. Referring now more particularly to Fig. 9, it may be seen that the lever 244 has oppositely extending arms 250 and 252, each of which terminates in a short reversely extending portion spaced from an outwardly extending portion. Transversely extending pins 254 are fixedly secured to the outwardly and reversely extending portions of the lever arms at equal distances from the axis of rotation of the lever. These pins are utilized operatively to connect the lever to the solenoid plungers 248, the latter being hingedly connected at their upper ends to connecting links 256 by pins 258 extending through the links and plungers. The connecting links are slotted near their upper ends as indicated by the reference character 250 (see Fig. 10) to receive the pins 254 and the upper ends of the links are tapped to receive adjusting screws 262 held in adjusted position by jam nuts 264. Thus, by adjusting the screws 262, the lower ends of which bear against the pins 254, the location of the plunger relative to the lever may be varied to control the angular movement of the lever by the solenoids. The connecting links 260 are held in place on the pins 254 by means of washers 266.

The solenoid actuated lever 244 is biased to a normal horizontal position by a spring 268 wound about a boss formed integral with the end support 240 and having its ends embracing a pair of pins 270 and 272, the former of which is secured to the support 240 and the latter to the lever 244.

The linkages interconnecting the solenoids and lever 244 are so constructed and arranged that when either of solenoids 54 or 56 is energized, the lever is rocked in a counterclockwise (looking at Fig. 10) direction, the solenoid 56 rotating the lever a greater extent than solenoid 54. When either of solenoids 58 or 60 is energized, the lever is rocked in the opposite or clockwise direction, the solenoid 60 rocking the lever to a greater extent than the solenoid 58.

When any of the solenoids is energized, the resulting movement of the lever 244 is transmitted to the lever 246 through a resilient connection including a spring 274 and opposed pins 276 and 278 fixedly secured to upwardly extending bosses formed in levers 244 and 246, as best indicated in Figs. 9 and 10. The spring 274 is wound about an extension 280 of the hub of lever 244, and the ends of the spring embrace the two pins in a manner similar to that in which the ends of spring 268 encircle the pins 270 and 272. The spring 274 serves also normally to bias the lever 246 to a horizontal position but whenever the lever 244 is rotated by the solenoids, the lever 246 is rotated in the same direction through the resilient connection.

The rotation of the lever 246 is made to be gradual and at a uniform rate by means of two dash pots 282 (only one of which has been shown in Fig. 10 better to illustrate other features), which are provided with air bleed valves 284 for adjusting the rate of movement. The lever 246 is connected to the dash pots by means of its opposed arms 286 and downwardly extending links 288 pinned at their upper ends to the arms 286 and at their lower ends to the pistons 290 70

The lever 246 is operatively connected to the pilot valve 232 by means of an arm 292 hingedly secured to a downwardly extending link 294, the lower end of which is hingedly connected to a

two-part floating lever 296 which in turn is hingedly connected by a pin 298 to the upper end 300 of the reciprocable tubular pilot valve piston 301. The arm 292 of the lever 246 is spaced from the arms 286, as best illustrated in Fig. 9, and it is provided with an integral cam defining extension 302 operating the previously referred to switch 62. The switch 62 is of the normally closed type and is operated upon movement of a flexible switch actuating member 304 engaging a switch button 306 and to the upper end of which is secured a roller 308 engageable with the cam defining portion 302. The cam is so shaped and arranged relative to the roller that in its normal position, or when rotated clockwise (as viewed in Fig. 10) pressure is maintained on the roller and flexible portion 304 to maintain the switch 62 open. However, a slight counterclockwise rotation of the cam 302 removes the pressure whereby the flexible member 304 moves outwardly and permits the switch to close.

The lever 246 is counterbalanced by a weight arm 310 extending therefrom in a direction opposite to the arm 292.

The speed vane 104 is also connected to the floating lever 296 by means of which the pilot valve is controlled. This connection extends from the speed vane shaft 206 to the floating lever through a lever 312 fixedly secured by a pin 313 to the shaft 206 and the slotted end 314 of which is hingedly secured to the upper end of a link 316 having its lower end hingedly secured to the floating lever. As already indicated, the shaft 206 and consequently the lever 312 is biased to a normal (horizontal) position in which it is indicated in Figs. 9 and 10 by the spring 220. The spring is wound around the end of the thrust collar 216 extending into the control box through the bed plate wall 224, as illustrated best in Fig. 9. The ends of the spring embrace a pin 318 secured to the bed plate wall and the grooved end 320 of the lever 312.

The pilot valve 232 and its connection to the floating lever 296 are best illustrated in Figs. 8 and 10 to which reference will now be had. Referring more particularly to Fig. 8, it may be seen that tubular piston 301 is connected by a threaded joint to the upper portion 300 connected to the floating lever. The connection between the two parts of the piston is sealed by a flexible sealing diaphragm 322 held in place at its center by a collar 324 formed integrally with member 300. The outer peripheral portion of the sealing diaphragm is held between the body of the pilot valve and the bed plate wall 226 by the previously referred to securing screws 234. A small passageway 326 provides communication between the interior of the valve piston 301 and the diaphragm to balance the pressures acting on the piston.

The pilot valve controls the pressures existing within the pressure chambers 134 and 184 of the bypass and lowering valves, respectively, by controlling the flow of oil from these chambers to the return passage 110. Under normal conditions, the bypass valve pressure chamber is connected to the return chamber but the pressure chamber of the lowering valve is cut off from communication with the return chamber. The bypass pressure chamber is connected to the pilot valve through the previously referred to conduit 138 and a suitable coupling 328 leading to an annular port 330 formed in the body of the pilot valve. Under normal conditions, the lower end of the pilot valve piston 301 is in a

11

position to open this port whereby the pressure chamber communicates with the return chamber through the conduit 138, the port 330, an outlet port 332 formed at the lower end of the pilot valve body, and a conduit 334 leading to the return chamber 110 through a coupling member 336, as illustrated in Fig. 4. Under normal conditions, the flow of liquid from the lowering valve pressure chamber 184 is cut off by the pilot valve, the lower end of which closes a port 338 connected to the pressure chamber through the conduit 190.

When the elevator is being raised, the closing of the port 330 is controlled by the piston 301 which, in turn is controlled conjointly by one or the other of solenoids 54 or 56 and the speed vane, and when the elevator is being lowered the opening of port 338 is similarly controlled by the piston under the conjoint control of one or the other of solenoids 58 or 60 and the speed vane.

Before considering the operation of the system when raising and lowering the elevator, it may be well first to set forth the normal positions of the various parts of the system. Thus when the elevator car switch 32 is in its neutral position, wherein it is indicated in Fig. 2, the various pilot valve operating valve solenoids 54, 56, 58, and 60 are all deenergized. The switch 62 is, therefore, open and the motor switch controlling solenoid 52 is deenergized so that the pump motor and pump are out of operation. Under these conditions, the check valve 100 is closed and the speed vane is at its normal position, as indicated in Fig. 5. The lowering valve 108 is closed by reason of the force exerted thereon by its biasing spring 178 and by the pressure existing in chamber 184, the flow of liquid from which is prevented by the normally closed pilot valve port 338. The bypass valve is open by reason of the force exerted thereon by the relatively light spring 132 and because the pressure chamber 134 is under no pressure since the liquid therefrom is permitted to flow to the return chamber 110 through the conduit 138 and the normally open port 330 of the pilot valve. The levers 244, 246, and 312 of the control apparatus are also in their normal positions, that is, the horizontal positions in which they are indicated in Figs. 9 and 10.

In case it is desired to raise the elevator at high speed, the handle 64 of the car switch is moved counterclockwise to energize the solenoid 58 through a circuit that has been previously described and which, it may be remembered, extends through the upper limit switch 34. The solenoid winding immediately moves downwardly its plunger 248 and associated link 256 with the result the lever 244 is rotated counterclockwise (as viewed in Fig. 10) through an angle determined by the adjustment of adjusting screw 262. The lever 244 tensions the springs 268 and 274, the former of which thus exerts a biasing force tending to return the lever 244 to its normal position, and the latter of which exerts a turning force on the lever 246 tending to turn the latter in the same direction as the lever 244, that is, in a counterclockwise direction. The spring 274 turns the lever 246 at a uniform rate which is determined by the adjustment of valves 284 of the dash pots 282, which, it may be remembered, are operatively connected to the lever 246 through links 288.

As soon as lever 246 rotates, the switch 62 is closed as the cam member 302 permits the resilient switch actuating member 304 to move outwardly to remove the pressure from the switch

12

operating button 306. When switch 62 closes, a circuit is completed for the motor switch operating solenoid 52, with the result that the pump motor circuit is closed and the pump is started. 5 As soon as the pump starts, oil flows from the discharge side of the pump into the valve passageway 98 through conduit 24. The oil at this time, however, is bypassed to the reservoir inasmuch as the bypass valve is open, the oil flowing from passageway 92 to the reservoir through the port 118, the passageways 120, the return chamber 110, and conduit 22. As a result, the motor and pump accelerate quickly and at but a very light load to full speed.

10 The pressure in chamber 98 is gradually built up by the closure of the bypass valve. There is an initial slight loss of pressure between port 118 and return chamber 110 when oil flows through passageway 136 in the bypass valve piston 122 into the pressure chamber 134. This liquid is initially free to flow to the return chamber 110 through the conduit 138 and the normally open port 330 of the pilot valve.

15 It has already been indicated that the lever 246 gradually rotates in a counterclockwise direction. As it does so, the lever arm 292 gradually depresses the left end (as viewed in Figs. 9 and 10) of the pilot valve controlling floating lever 296. As this end is depressed, the pilot

20 valve piston 301 is moved downwardly, gradually to cut off the flow of oil from the pressure chamber 134. Consequently, the pressure in this chamber is increased to equal that in the passageway 92 and port 118. The effective area of the

25 left side of the piston 122 (the area open to the pressure chamber) is greater than that of the right side of the piston (the area open to pressure in passageway 92), so that when the pressures in the latter and in the pressure chamber

30 are equal, the entire piston assembly moves to the right compressing the relatively light spring 132 and further restricting the flow of oil past the bypass valve into the return chamber 110. The pressure in the passageway 98 thus increases

35 and the bypass valve 112 is moved in closing direction until the pressure in passageway 98 exceeds that in chamber 102, which pressure is created by the hydrostatic head of oil in the elevator system and the weight of the elevator car and associated parts. When this occurs, the check valve 100 opens and a portion of the oil flows past the vane 104, rotating it in a counterclockwise direction, and the elevator is started in upward direction at a slow rate.

40 The speed vane 104 consequently rotates the lever 312 in a counterclockwise direction, and the latter lifts the righthand end of the floating lever 296 through the connecting link 316. This upward movement of the floating lever tends to 45 counteract the effect of movement of lever 246 by the spring 274, that is, it has a tendency to prevent closure of the port 330 by the movable pilot valve piston 301.

46 If the speed of the elevator is increased to too great a rate, the speed vane will be displaced so far that the righthand end of the floating lever will be lifted enough to reopen the port 330, thereby bleeding away all the liquid entering the bypass valve pressure chamber 134 and causing the bypass valve partially to reopen.

51 As the bypass valve is progressively closed under the conjoint control of the levers 246 and 312, liquid flows past the vane 104 so that the latter is no longer capable of movement, and finally the 56 lever 246 moves the pilot valve piston 301 down

13

completely to close port 330 of the bypass valve. Thus the elevator moves upwardly at its maximum speed and the various parts of the system remain in this position during the upward travel of the elevator at its high speed.

If during the period when the bypass valve is being closed the speed of the elevator is less than it should be, the speed vane returns towards its normal position, that is, it moves in a clockwise direction. This movement depresses the right end of the floating lever so that both the lever 246 and the speed vane lever 312 tend to move the pilot valve member downwardly to close the port 330. This has a tendency to increase the flow of liquid to the elevator and to increase the speed of the latter to the desired value.

When the elevator approaches the landing at which it is desired to stop, either the upper limit switch 34 or the car switch is operated to interrupt the circuit to the solenoid 56. When the solenoid is deenergized, its plunger is released and the springs 268 and 274 return the levers 244 and 246 to their normal horizontal positions, the spring 268 acting on lever 244 and the latter in turn acting on lever 246 through spring 274. The movement of lever 246, however, is at a gradual and uniform rate by reason of the control action of the dash pots 282.

As the lever 246 rotates in a clockwise direction, it raises the left end of the floating lever, thereby partly opening port 330 to reduce the pressure in the pressure chamber 134 of the bypass valve so that the bypass valve commences to open. As oil begins to flow through the bypass valve, the flow past the speed vane 104 is reduced and it is urged in a clockwise direction by spring 220. This movement lowers the right end of the floating lever with the result that the pilot valve piston 301 is moved in a direction to close the port 330. The pilot valve is thus constrained to take an intermediate position so that the bypass valve opens at a uniform rate, thereby to decelerate the elevator at a uniform rate.

When the elevator stops, the check valve 108 closes by gravity to prevent reverse flow. The bypass valve, however, continues to open until it strikes the closure cap 126, or a stop ring which may be inserted between the closure cap and the valve body to limit its movement for the purpose of preventing the bypass from opening so far that insufficient pressure difference will exist between passageway 92 and return chamber 110 to initiate closing movement of the piston valve when liquid is prevented from flowing from the pressure chamber 134.

The lever 246 continues to rotate in a clockwise direction until it reaches its normal position, at which time the switch 62 is opened to deenergize the motor controlling solenoid 54 and the pilot valve piston 301 is returned to its normal position to open port 330, the port 338 remaining closed.

For extreme accuracy in effecting landings or to raise the elevator a short distance only, it is desirable to raise the elevator at a low speed. This can be accomplished by energizing the solenoid 54, the associated adjusting screw 262 of which is adjusted so that full stroke of the associated plunger 248 will rotate the lever 244 through a lesser angle than that through which the lever is rotated upon energization of solenoid 56. If the elevator be assumed to start from rest, the operation is the same as that described above with exception that lever 246 is rotated a lesser angle corresponding to the lesser angle of

14

rotation of lever 244. Further increase in flow of liquid to the elevator at this time rotates vane 104 further in a counterclockwise direction, lifting the right end of the floating lever and opening the port 330 to increase the flow of oil from the pressure chamber 134 and thereby reducing the pressure behind the piston 122. The flow of liquid to the elevator is thus maintained at a reduced volume, the balance of the oil pumped being returned to the reservoir through the bypass valve.

If for any reason the resistance encountered by the elevator should increase, as for instance by a decreased hydrostatic head acting on the bottom of the plunger as it rises, the flow through the bypass valve will increase and that to the elevator will decrease accordingly. Should this occur, the speed vane drops partially to its center position, moving the pilot valve piston 301 to close the port 330 sufficiently to reestablish the desired rate of flow to the elevator.

When it is desired to reduce the speed of the elevator from full speed to low speed, the solenoid 56 is deenergized and solenoid 54 energized. This reduces the angular displacement of the lever 244 with the result that lever 246 moves gradually into alignment with lever 244. During this movement, the port 330 will be opened somewhat to open the bypass valve the desired amount. When the speed of the elevator is reduced to the value for which the controls are adjusted, the pilot valve member 301 is brought back by the vane to an intermediate position at which the port 330 is opened sufficiently to maintain the desired low speed.

When it is desired to stop the elevator during its travel at low speed, it is necessary only to deenergize the solenoid 54, in which event the elevator is stopped in the same manner as described above in connection with stopping the elevator during its travel at high speed.

It should be understood that there is a position of the pilot valve piston 301 in which the port 330 is partly closed so that the pressure in the bypass pressure chamber 134 bears the same ratio to the pressure in passage 92 as the area of the face of the bypass valve piston exposed to pressure in the passage 92 bears to the area of a left-hand side of the piston (neglecting the small force exerted by the right spring 132). In this position of the pilot valve piston, the bypass valve will neither open nor close. Any slight deviation of the pilot valve piston from this position will cause slow motion of the bypass valve in the opening or closing direction, as the case may be, while a considerable pilot valve motion will produce a correspondingly rapid motion of the bypass valve.

It should also be understood that for each rate of oil flow past the speed vane 104, to or from the elevator, there is a corresponding angular position of the vane, as it is acted upon only by the flow of oil and its motion is resisted by the spring 220. Since, for stable operation at constant pressure, the position of the pilot valve piston 301 is determined, it may be seen that each angular position of the vane has a corresponding position of the floating lever 296. If the lever is caused to assume any such position and adequate hydraulic liquid supply is provided, a corresponding speed will be maintained.

In other words the low speed operation of the valve is wholly dependent on the vane 104. Were that end of the lever 296, to which the vane is attached, regarded as a stationary pivot, the movement of the other end of the lever would

result only in a more or less rapid closing of valve 114 but in any case a closing to the fully closed position. The actuation of solenoid 54 has the effect of placing the pilot valve 301 with respect to port 339 in such a position that the pressure relief through the pilot valve is slightly less than the pressure intake through passage 136. The end of lever 296 associated with solenoid 54, which solenoid produces this pressure differential, may after actuation of the solenoid be regarded as a 10 fixed fulcrum. Thereafter as the fluid flow past the vane accelerates, the vane moves to counter the solenoid placement of the pilot valve 301. This has the effect of gradually equating the pressures on each side of valve 114 as the valve moves 15 toward the closed position or creating a situation with respect thereto at some point in the course of valve 114 travel where the pressure relief is equal to the pressure intake through passage 136. At this point the valve movement will necessarily stop because of this lack of pressure differential, so producing the reduced flow rate desired.

For the sake of efficiency, the bypass should be entirely closed during full speed travel of the elevator. To insure this closing, the adjusting screw 262 associated with solenoid 56 is so adjusted as to produce rotation of levers 244 and 246 beyond the position corresponding to the full speed of which the pump is capable; this additional rotation of the levers depresses the pilot valve member 301 beyond the position for balancing the bypass valve and consequently the latter is fully closed.

To lower the elevator, it is necessary to energize either solenoid 58 or 60 depending upon whether slow or high speed is desired. The action is similar to that in raising the elevator except that the lowering valve 100 is normally closed as the pilot valve port 338 is normally closed by the piston 301 of the pilot valve. The lowering of the elevator is effected by gravity and when either of solenoids 58 or 60 is energized, the switch 62 remains open by reason of the configuration of the cam 382 formed as a part of lever 244, this configuration being such that when the levers 244 and 246 are moved clockwise by energization of solenoids 58 or 60 the switch remains open.

Assuming first that it is desired to lower the elevator at high speed, then the solenoid 60 is energized. The plunger 243 of this solenoid effects movement of lever 244 in a clockwise direction, with the result that the lever 246 is slowly and at a uniform rate moved in the same direction. The solenoid and speed vane again exert opposing effects on the floating lever 296, the solenoid tending to open the port 338, and the speed vane tending to close the port in the event that lowering speed is too great. The extreme angular travel of the vane is designed to be greater than that produced by the highest desired lowering speed, while the maximum angular travel of lever 244 is restricted to produce a lesser movement of the pilot valve member 301. Consequently, the speed is governed up to the highest possible setting of the adjusting screws 262.

It should be noted that the lowering speed is limited by the size of the opening of the lowering valve port 174 and the minimum working pressure of the elevator. The only time that the valve fails to maintain a constant lowering speed is when the above limiting conditions are reached with minimum load and maximum speed adjustment.

Should the pressure within passage 92 or in the system rise to some value above a desired maxi-

mum pressure while the elevator is being raised, the pressure is reduced to the predetermined pressure by the relief valve operation of the bypass valve. In considering this phase of the invention, let A be the projected area of the face of the bypass valve exposed to the operating pressure (the right side), and let A' be the projected area of the lefthand face of the piston open to pressure in the pressure chamber, P be the operating pressure in passageway 98, P' that in the pressure chamber, and I be the force exerted by spring 132. It is apparent when the valve is in equilibrium

$$P' = \frac{PA + I}{A'}$$

In other words, the pressure is lower in the pressure chamber than in passageway 98 by the ratio of the area of the valve face to the piston face, except for the relatively small correction for spring 132. When, as during full speed upward travel of the elevator, the pilot valve entirely cuts off the flow of liquid from the pressure chamber, other means must be provided to prevent the pressure in this chamber from rising above the setting of the overpressure relief spring 146 unless the pressure P is actually above the limit desired to be maintained. To accomplish this purpose, the discharge port 148 is so shaped at its opening into piston chamber 144 that a very small opening will be uncovered by initial motion of piston 142. This end is attained by providing the tapered groove 150 at the end of passageway 148. As the piston moves initially, a small portion of this groove is uncovered and as the piston moves further, the area of the exit passage finally exceeds that of the passage 136. The escape of fluid from pressure chamber 134 thus provided will prevent further rise in pressure in the pressure chamber as long as this rise is due only to entrance of liquid through passageway 136.

However, if the pressure in passageway 98 exceeds the predetermined pressure P, that in chamber 134 will exceed P' with the result that the piston 142 will move further to the right (as viewed in Fig. 5), thus uncovering enough of the port 148 to exhaust oil from the pressure chamber faster than it can enter through the passageway 136. As a result, the bypass valve piston 122 will move to the left and open the bypass ports 120 the necessary extent to limit the pressure in chamber 98 to the desired value. It may be noted that the passages 148 may be relatively large so as to permit very rapid evacuation of liquid from pressure chamber 134 and a very rapid full opening of the bypass valve. This construction provides against destructive pressure rise in the event of sudden obstruction of flow of liquid to the elevator.

When the bypass valve has been opened as a result of excessive pressure, it will move to and remain at a position that will maintain the desired pressure in passageway 98, since it is designed to pass the entire output of the pump with which it is used at a pressure much less than the desired pressure at which the relief is had. During bypassing because of overpressure, the relationship between the pressures and areas set forth above holds, and fails to hold only when the bypass valve is bearing against one of the stops which limits its travel.

Any external change resulting in a decrease in pressure in the passageway 98 results in a decrease in pressure in chamber 134 with the result that the relief valve piston 142 moves back to

cut off the flow of liquid through the passage-way 148 and with the further result that the bypass valve is closed.

While the above illustrative embodiment of the invention has included a pump and motor as the source of fluid under pressure, it should be noted that it is possible to use other sources and retain advantages accruing from the use of the valves. For instance, the source may well be of any type providing a substantially constant volumetric flow—and certain of the advantages of the invention are retained when the source is of the variable flow type. Likewise, the invention is applicable to systems other than hydraulically actuated elevators. It is also applicable to automatically controlled systems because of the ease with which the valve may be controlled.

What I claim as new and desire to secure by United States Letters Patent is:

1. In a pilot operated valve mechanism comprising a valve casing having an inlet passage communicating with a high pressure region and an exhaust passage communicating with a low pressure region, a main valve between said inlet passage and exhaust passage and an actuating piston connected thereto, and the casing and the back side of the piston defining a pressure chamber, the combination including, a small passage providing communication between the inlet passage and said pressure chamber, means including a pilot valve providing communication between said pressure chamber and the exhaust passage for relieving the pressure in said chamber, means including a lever operatively connected to said pilot valve to move the latter to relieve the pressure in said chamber to open said valve, means including a second lever resiliently connected to said first-mentioned lever for moving the latter, and means including movement restraining means operatively connected to said first-mentioned lever for controlling the rate of movement of said pilot valve.

2. In a pilot operated valve mechanism comprising a valve casing having a fluid flow passage leading from an inlet under pressure to an exhaust at a lower pressure, an interconnected valve and an actuating piston therefor for controlling the flow of fluid through said passage, said valve separating said passage into an upstream high pressure side and a downstream low pressure side the casing and the back side of the piston defining a pressure chamber, the combination including, a small passage providing communication between the high pressure side of said valve and said pressure chamber, means including a pilot valve providing communication between said pressure chamber and the low pressure side of said valve for relieving the pressure in said chamber, means for operating said pilot valve to relieve the pressure in said chamber, said means including a floating lever connected between its ends to said pilot valve and a movable lever connected to one end of said floating lever, and means including means forming an inlet passage leading from the high pressure region of said fluid flow passage to a fluid supply, a vane in said inlet passage movable in response to the rate of fluid flow through the last said passage and connected to the other end of said floating lever for controlling the operation of the pilot valve in response to the rate of flow of fluid in said inlet passage.

3. In a pilot operated valve mechanism comprising a valve casing having a fluid relief passage, an interconnected valve and an actuating piston therefor for controlling the flow of fluid

through said relief passage, the casing and back side of the piston defining a pressure chamber, the combination including, a small passage providing communication between the front of the piston and the pressure chamber, means including a pilot valve providing communication between the pressure chamber and a low pressure region for relieving the pressure in said chamber, means for operating said pilot valve to control the relief of pressure in the chamber, means forming a fluid flow passage, and means including a member in the fluid flow passage responsive to the rate of fluid flow therethrough for modifying the pilot valve operating means in response to the rate of fluid flow through said fluid flow passage.

4. A pilot valve mechanism for controlling a fluid flow regulating valve, including in combination, a movable pilot valve member, a floating lever connected intermediate its ends to said valve member, a rotatable lever operatively connected to one end of said floating lever, means for rotating said lever in opposite directions to move said valve member, and a lever rotatable into different positions and in different directions in response to the rate and direction of fluid flow and operatively connected to the other end of said floating lever for controlling the position of the pilot valve member.

5. A pilot valve mechanism for controlling a fluid flow regulating valve, including in combination, a movable pilot valve member, a pair of valve ports associated therewith, said valve member normally closing one and normally opening the other of said ports, a floating lever connected intermediate its ends to said valve member, a rotatable lever operatively connected to one end of said floating lever, means biasing said lever to a normal position corresponding to the normal position of said valve member, means for rotating said lever in opposite directions to move said valve member relative to said ports, a second lever rotatable into different positions and in opposite directions in response to the rate and direction of fluid flow and operatively connected to the other end of said floating lever for controlling the position of the pilot valve member, and means for biasing said second lever into a predetermined position occupied thereby when no fluid is flowing.

6. In a pilot operated valve mechanism comprising a valve casing having an inlet passage communicating with a high pressure region and an exhaust passage communicating with a low pressure region, an interconnected valve and an actuating piston therefor, a spring for biasing the valve normally to close communication between said passages, and the casing and the back of the piston defining a pressure chamber, the combination including, a small passage providing communication from a region between the piston and valve in the inlet passage to said pressure chamber, means including a normally closed pilot valve providing communication between said pressure chamber and the low pressure region for relieving the pressure in said chamber to effect opening of the valve, operating means for opening said pilot valve to relieve the pressure in said chamber, movement restraining means associated with said operating means to effect opening movement of the pilot valve at a uniform rate, means forming a branch passage leading from said inlet passage, and means controlling said pilot valve in response to the rate of flow of fluid through said branch passage and tending

to close said pilot valve in the event the pilot valve is opened too rapidly and the flow of fluid in the branch passage increases too rapidly.

7. In a pilot operated valve mechanism comprising a valve casing having an inlet passage communicating with a high pressure region and an outlet passage communicating with a low pressure region, an interconnected normally open valve and an actuating piston therefor, the valve normally providing communication between said passages and the casing and the back of the piston defining a pressure chamber, the combination including, a small passage providing communication from a region between the piston and valve in the inlet passage to said pressure chamber, means including a normally open pilot valve providing communication between said pressure chamber and the low pressure region for relieving the pressure in said chamber, and movable to increase the pressure in said chamber to effect closure of the valve, means for moving said pilot valve, restraining means controlling said moving means to effect movement of the pilot valve at a uniform rate, means forming a branch passage leading from said inlet passage, and means controlling said pilot valve in response to the rate of flow of fluid through said branch passage for preventing too rapid movement of the pilot valve and change in rate of fluid flow.

8. In a pilot operated valve mechanism comprising a valve casing having an inlet passage communicating with a high pressure region and an outlet passage communicating with a low pressure region, an interconnected normally open valve and an actuating piston therefor, a spring for biasing the valve normally to provide communication between said passages, and the casing and the back of the piston defining a pressure chamber, the combination including, a small passage providing communication from a region between the piston and valve in the inlet passage to said pressure chamber, means including a normally open pilot valve providing communication between said pressure chamber and the low pressure region for relieving the pressure in said chamber and movable to increase the pressure in said chamber to effect closing of the valve, operating means for closing said pilot valve to build up the pressure in said chamber to close said valve and for opening said pilot valve to relieve the pressure in said chamber to open said valve, movement restraining means associated with said operating means to effect closing and opening movements of the pilot valve at a uniform rate, means forming a branch passage leading from said inlet passage, and means controlling said pilot valve in response to the rate of flow of fluid through said branch passage and tending to open said pilot valve in the event the pilot valve is closed too rapidly and the flow of fluid in the branch passage increases too rapidly and tending to close said pilot valve in the event the pilot valve is opened too rapidly and the flow of fluid in the branch passage decreases too rapidly.

9. A start-cushioning valve for use with a source of fluid under pressure and a device to be actuated by the fluid, including in combination, a fluid inlet passage, a fluid bypassage, a valve member between said passages having a portion thereof open to said fluid passage, a spring biasing said valve member to an open position wherein said passages are in communication, and means for gradually closing said valve when fluid under pressure is admitted to said fluid inlet pas-

sage, said last mentioned means including a piston operatively connected to said valve member and having an area greater than said portion of the valve member, a cylinder in which said piston is movable, the cylinder and back side of the piston defining a pressure chamber, and a small passage interconnecting said fluid inlet passage and pressure chamber.

10. A hydraulic system, including in combination, an electric motor, a positive displacement pump having an outlet and driven by said motor, a conduit connected to the pump outlet, a fluid bypassage, a valve member between said conduit and bypassage having a portion thereof open to said conduit, a spring biasing said valve member to an open position wherein said conduit and bypassage are in communication, means for energizing said motor, and means for gradually closing said valve when said motor is energized whereby said motor is enabled to accelerate to full speed at low pressure, said last-mentioned means including a piston operatively connected to said valve member and having an area greater than said portion of the valve member, a cylinder in which said piston is movable, the cylinder and back side of the piston defining a pressure chamber, a small passage interconnecting said fluid passage and pressure chamber, a normally open pilot valve for controlling the relief of pressure in said chamber, movable pilot valve operating means, and means delaying operation of said operating means, said operating means being effective upon initial movement to operate said motor energizing means.

11. A hydraulic system, including in combination, an electric motor, a positive displacement pump having an outlet and driven by said motor, a conduit connected to the pump outlet, a fluid bypassage, a valve member between said conduit and bypassage having a portion thereof open to said conduit, a spring biasing said valve member to an open position wherein said conduit and bypassage are in communication, means for controlling the energization of said motor, and means for gradually opening said valve and thereafter deenergizing said motor, said last-mentioned means including a piston operatively connected to said valve member and having an area greater than said portion of the valve member, a cylinder in which said piston is movable, the cylinder and back side of the piston defining a pressure chamber, a small passage interconnecting said fluid passage and pressure chamber, a normally open pilot valve for controlling the pressure in said chamber operable to restrict flow of fluid from the pressure chamber when the motor is energized, movable pilot valve operating means for opening said pilot valve, and means delaying operation of said operating means, said operating means being effective after movement of said pilot valve to its open position to deenergize said motor.

12. A hydraulic system, including in combination, an electric motor, a positive displacement pump having an outlet and driven by said motor, a conduit connected to the pump outlet, a fluid bypassage, a valve member between said conduit and bypassage having a portion thereof open to said conduit, a spring biasing said valve member to an open position wherein said conduit and bypassage are in communication, means for controlling the energization of said motor, means for gradually closing said valve when said motor is energized whereby said motor is enabled to accelerate to full speed at low pressure, said last-

mentioned means including a piston operatively connected to said valve member and having an area greater than said portion of the valve member, a cylinder in which said piston is movable, the cylinder and back side of the piston defining a pressure chamber, a small passage interconnecting said fluid passage and pressure chamber, a normally open pilot valve for controlling the relief of pressure in said pressure chamber, movable pilot valve operating means, and means restraining operation of said operating means, said operating means being effective upon initial movement to operate said motor energization controlling means, and means for gradually opening said valve and then deenergizing said motor, said means including the pilot valve, the pilot valve operating means and the restraining means.

13. A hydraulic system, including in combination, an electric motor, a positive displacement pump having an outlet and driven by the motor, a pilot operated valve mechanism comprising a valve casing having an inlet passage connected to said outlet, a combined outlet and return passage, and an exhaust passage, a check valve between the inlet and the outlet and return passages preventing return flow from the latter to the former passage, a valve biased to closed position located between the exhaust and outlet and return passages and having a piston connected thereto, the back side of said piston and the casing defining a pressure chamber, a valve biased to open position between the inlet and exhaust passages and having a piston connected thereto, the back side of said piston and the casing defining a second pressure chamber, a small passage providing communication between the outlet and return and the first pressure chamber, a second small passage providing communication between the inlet passage and the second pressure chamber, means including a pilot valve and a pair of spaced ports controlled thereby for controlling the relief of pressures in said chambers, said pilot valve occupying a normal position wherein said first small passage is closed and the second open, means for selectively moving said pilot valve selectively to open said first small passage and to close the second, thereby to effect selective opening of said normally closed valve and closing of the normally open valve, said means including a floating lever connected intermediate its ends to said pilot valve, a first rotatable lever connected to one end of said floating lever, a second rotatable lever resiliently connected to the first and biased to a predetermined position, a first pair of solenoids selectively energizable to rotate said second and first levers in one direction to move said pilot valve into different closing positions relative to said second small passage, and a second pair of solenoids selectively energizable to rotate said second and first levers in the opposite direction to move said pilot valve into different opening positions relative to said first small passage, a pair of dashpots secured to said first lever to cause it to move at a uniform rate, whereby said pilot valve is moved at a uniform rate, means for controlling said pilot valve in response to the rate of fluid flow through said combined outlet and return passage, said last-mentioned means including a pivotally movable vane in said passage, resilient means biasing it to a central normal position, and a lever connecting the vane to the other end of said floating lever, and motor controlling switch means operable by said first rotatable lever, said switch means being operable to ener-

gize said motor upon initial rotation of said first lever in said opposite direction by energization of either of said first pair of solenoids and to deenergize said motor upon final return rotation of said lever when said solenoids are deenergized.

14. In apparatus of the class described, the combination including, a fluid flow regulating valve, and means responsive to the rate of fluid flow for controlling the position of said valve, said last mentioned means including a vane movable in opposite directions in response to the direction of fluid flow and to an extent determined by the fluid velocity and means controlled by said vane for continuously varying the position of said regulating valve thereby to vary continuously the rate of flow through said valve in proportion to the movement of the vane.

15. In apparatus of the class described, the combination including, a fluid flow regulating valve, and means responsive to the rate of fluid flow for controlling the position of said valve, said last mentioned means including a semi-cylindrical housing having a port in each of the two opposite quadrants of its cylindrical surface, a vane closely fitting and swingably mounted in said housing, and means biasing said vane to a mid position wherein it obstructs the passage between the ports and from which it is movable in response to pressure from either port in proportion to the rate of fluid flow.

16. Fluid flow regulating apparatus comprising a normally open by-pass valve adapted to by-pass fluid flowing in a conduit, means including a piston connected to said valve and to which is applied the pressure difference across the seat of said by-pass valve for gradually closing said by-pass valve, and means responsive to the rate of fluid flow in said conduit for controlling the movement of said piston and thereby of said by-pass valve in response to the rate of flow of fluid.

17. Fluid flow regulating apparatus as claimed in claim 16 including electromagnetic means controlling said by-pass valve closing means for rendering said means operable to close said valve.

18. Fluid flow regulating apparatus comprising a normally open by-pass valve adapted to by-pass fluid flowing in a conduit, means including a piston connected to said by-pass valve and a pilot valve controlling the pressure applied to said piston for controlling the position of said by-pass valve, and means including a movable vane biased to a position to obstruct flow through the conduit and movable to an extent proportional to the rate of fluid flow through the conduit for controlling the pilot valve to vary the pressure applied to the piston to effect opening movement of said by-pass valve when the flow past the vane is above a predetermined value and to effect closing movement of said by-pass valve when the flow is less than said value.

19. Fluid flow regulating apparatus comprising a by-pass valve controlling the flow of fluid through a conduit, means including a piston connected to said valve and a pilot valve controlling the pressure applied to said piston for controlling the position of said by-pass valve, and means including a movable vane biased to a position to obstruct flow through the conduit and movable to an extent proportional to the rate of fluid flow through the conduit for controlling the pilot valve to vary the pressure applied to the piston to effect closing movement of said valve when the flow past said vane is above a predetermined

value and to effect opening movement of said valve when the flow is less than said value.

20. In combination with a valve mechanism including a valve casing having a fluid flow passage and a main valve in said passage dividing said passage into an upstream high pressure side and a downstream low pressure side; a pilot valve mechanism governing the main valve to control the rate of acceleration of fluid flow in the passage comprising a piston connected to said main valve, the back side of the piston and a portion of the casing being formed to define a pressure chamber, a small passage providing communication between the high pressure side of said valve and the pressure chamber to urge closure of the valve, a pressure relief passage providing communication between the pressure chamber and the low pressure side of said valve, a pilot valve in the pressure relief passage, and means operative to effect different degrees of opening of said pilot valve, relieving the pressure in said pressure chamber at different rates, so effecting different rates of movement of said main valve.

21. In combination with a valve mechanism including a valve casing having a fluid flow passage and a main valve in said passage dividing said passage into an upstream high pressure side and a downstream low pressure side; a pilot valve mechanism governing the main valve to control the fluid flow in the passage comprising a piston connected to said main valve, the back side of the piston and a portion of the casing being formed to define a pressure chamber, a small passage providing communication between the high pressure side of said valve and the pressure chamber to urge closure of the valve, a pressure relief passage providing communication between the pressure chamber and the low pressure side of said valve, a pilot valve in the pressure relief passage, means including a lever operatively connected to said pilot valve to move the pilot valve to relieve the pressure in said chamber, and means including a second lever resiliently connected to said first lever for moving the latter.

22. The combination claimed in claim 21 wherein movement restraining means are operatively connected to the first mentioned lever for controlling the rate of movement of said pilot valve.

23. In a pilot operated valve mechanism comprising a valve casing having a fluid flow passage, a main valve and an actuating piston for said valve connected thereto for controlling the flow of fluid through said passage, said valve separating said passage into an upstream high pressure side and a downstream low pressure side, the casing and back side of the piston defining a pressure chamber, the combination including a small passage providing communication between the high pressure side of said main valve and said pressure chamber, means including a pilot valve providing communication between said pressure chamber and the low pressure side of said main valve for relieving the pressure in said chamber, a floating lever connected between its ends to said pilot valve for operating said pilot valve to relieve the pressure in said chamber, manually controlled means operative to move one end of said lever, means forming a branch passage leading from said upstream high pressure side and a vane in said branch passage movable in response to the rate of fluid flow through the branch passage and connected to the other end of said floating lever for controlling the operation

of the pilot valve in response to the rate of flow of fluid in said branch passage.

24. A pilot valve operated mechanism comprising a valve casing having a fluid flow passage, a main valve in said passage dividing said passage into an upstream high pressure side and a downstream low pressure side, a piston connected to said valve, the back side of the piston and a portion of the casing being formed to define a pressure chamber, a small passage providing communication between the high pressure side of said valve and the pressure chamber to urge closure of the valve, a pressure relief passage providing communication between the pressure chamber and the low pressure side of said valve, a valve in the pressure relief passage, manually actuated means for operating the pilot valve to control the relief of pressure in the pressure chamber, means forming a branch passage leading from said upstream high pressure side, and means actuated by flow of fluid through the branch passage connected to the means for operating the pilot valve to vary the operation of the manually actuated means upon the pilot valve.

25. In combination with a main valve mechanism including a fluid flow passage, a valve in said passage, means defining a pressure chamber operatively associated with said valve to control the positioning of said valve and means for admitting fluid under pressure to said pressure chamber, a pilot valve mechanism for controlling the degree of opening of said main valve comprising a pilot valve having a port connected to effect the relief of pressure in the pressure chamber and a movable member to close variably said port, manually controllable means connected to the movable member to cause an initial positioning of the member with respect to the port, means forming a branch passage connected to the first said passage upstream of said valve, and a vane responsive to the flow of fluid in said branch passage connected to said movable member in opposition to the manually controllable means to modify the position imposed on said member by said manually controllable means to alter the rate of pressure relief of said pressure chamber, thereby to check the movement of the main valve.

26. In combination with a main valve mechanism including a fluid flow passage, a valve in said passage, means defining a pressure chamber operatively associated with said valve to control the position of said valve and means for admitting fluid under pressure to said pressure chamber; a pilot valve mechanism for controlling the degree of opening of said main valve comprising a pilot valve having a port connected to effect the relief of pressure in the pressure chamber and a movable member to close variably said port, manually controllable means connected to the movable member to cause an initial positioning of the member with respect to the port to move said main valve, means forming a branch passage connected to said fluid flow passage upstream of said valve, and means responsive to the flow of fluid in said branch passage connected to said movable member in opposition to the manually controllable means to modify the position imposed by said manually controllable means to alter the rate of pressure relief of said pressure chamber, thereby to check the movement of said main valve.

27. In combination with a main valve mechanism including a fluid flow passage, a valve in said passage, means defining a pressure chamber operatively associated with said valve to control

the positioning of said valve and means for admitting fluid under pressure to said pressure chamber; a pilot valve mechanism for controlling the degree of opening of said main valve comprising a pilot valve having a port connected to effect the relief of pressure in the pressure chamber and a movable member to close variably said port, a floating lever connected intermediate its ends to the movable member, manually controllable means connected to one end of said lever to cause an initial positioning of the member with respect to the port to move said main valve, means forming a branch passage connected to the first said passage upstream of said valve, and means responsive to the flow of fluid in said branch passage connected to the other end of said lever to counteract said manually imposed positioning of said member to alter the rate of pressure relief of said pressure chamber, thereby to check the movement of said main valve.

28. A pilot valve operated mechanism for providing a constant fluid flow rate in a conduit comprising a valve casing having a fluid flow passage adapted for insertion in said conduit, a main valve in said passage dividing said passage into an upstream high pressure side and a downstream low pressure side, a piston connected to said valve, means movably containing the piston, and, with the piston, forming a pressure chamber, a small passage providing communication between the high pressure side of said valve and the pressure chamber to urge the valve counter to the direction of urging of the pressure in said passage, a pressure relief passage providing communication between the pressure chamber and the low pressure side of said valve, a pilot valve in the pressure relief passage having a port for the relief of pressure in the pressure chamber and a movable member to effect a continuously variable closure of said port, manually controllable means for moving said movable member to a fixed position with respect to said port to adjust the opposing forces on said main valve to produce movement thereof, means forming a branch passage connected to the first said passage upstream of said valve, and means responsive to the flow rate in said branch passage connected to said movable member in opposition to said manually controllable means to modify the positioning of said movable member to balance the forces on each side of said valve.

29. A pilot valve mechanism for controlling a fluid pressure component for a fluid flow regulating main valve mechanism, said main valve mechanism including a fluid flow passage and a main valve in said passage movable in response to the difference in forces exerted in opposite directions thereon, one of said forces including a fluid pressure component comprising a pilot valve having a port therein adapted for fluid connection, and a movable member adapted to close variably said port, manually controllable means connected to the movable member to cause an initial position-

ing of the member with respect to the port to produce an unbalance of said forces to move the main valve, means forming a branch passage connected to the first said passage upstream of said valve, and means connected to said movable member responsive to the flow of fluid in said branch passage in opposition to the manually controllable means to modify the position imposed on said member by said manually controllable means to rebalance said forces to check the movement of the main valve.
